Primary Examiner — Mitchell Siegel(74) *Attorney, Agent, or Firm* — Christensen O'Connor Johnson Kindness PLLC(57) **CLAIM**

The ornamental design for a cooler, as shown and described.

DESCRIPTION

FIG. 1 is an upper front left perspective view a cooler showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is an upper front left perspective view of another embodiment of the cooler showing our new design;

FIG. 8 is a front elevation view thereof;

FIG. 9 is a rear elevation view thereof;

FIG. 10 is a right side elevation view thereof;

FIG. 11 is a left side elevation view thereof; and,

FIG. 12 is a top plan view thereof.

In FIGS. 1-6, the surfaces have a mottled appearance. In FIGS. 7-12, the surfaces have a simulated wood grain. The "RED BULL" name and symbol shown in broken lines in FIGS. 1, 2, 4, 5, 7, and 8, are included for purposes of illustrating environment and form no part of the claimed design. The configuration of the interior of the cooler design shown in FIGS. 1, 2, 7, and 8 is the same.
